ATTORNEY

UNITED STATES PATENT OFFICE.

JOHN W. EMBREY, OF LITTLE ROCK, ARKANSAS.

METHOD OF PERMANENTLY STRAIGHTENING KINKY HAIR.

Application filed August 2, 1927. Serial No. 210,177.

This invention relates to what may be termed a method for effecting a "permanent straight" on kinky hair, and more particularly to the hair of negroes.

5 A primary object of the invention is to provide a process or method whereby kinky hair may be straightened out and which will remain straightened.

10 Another object of the invention is to provide a method of straightening kinky hair which leaves it permanently straight without the use of any grease, acid or listerine so that the owner of the hair which is so treated may have a clean head and permanently 15 straight hair.

An apparatus for carrying out this method is shown in the accompanying drawings, in which:

20 Figure 1 represents a perspective view showing the use of apparatus for carrying out the method,

Fig. 2 is a similar view showing the hair arranged and held prior to the subjection thereof to steam, and

25 Fig. 3 is a similar view showing the hair wrapped and in place in the solution carrying flannel prior to insertion in the baking apparatus.

The method constituting this invention 20 consists in first washing and drying the hair to be straightened. The hair is then divided into section about one square inch more or less and placed out straight on the ferrule 1 of an ordinary waving apparatus, secured 25 to the ferrule in straight out position and held by twine 2, which is wrapped around the hair and ferrule and tied as is usual in permanent waving, the hair being saturated with lime sodium carbonate and oil 30 or other suitable liquid and a flannel 3 dipped into ammonia is placed over the hair and tied, as shown at 4. The protecting tapered tube, not shown, is placed over the flannel and the whole is then put into the 35 electrically heated baker 5. The steam generated from the chemicals while the hair is stretched and tied straight changes the

air shafts of each strand of hair so that when cooled, the hair will remain straight. It is, of course, understood that any suitable 50 caustic alkali may be used for saturating the flannel since the straightening of curly hair and the curling of straight hair are both dependent upon the treatment by steam containing alkali while the hair is being 55 stretched. The protecting tube may be made of any suitable material, preferably of paper and tinfoil or of either.

I claim:

1. A method of permanently straightening 60 curly hair which consists in dividing the hair in sections, placing the hair on a rod of a hair baking apparatus, securing the hair to said rod in straightened position, and then subjecting the hair to the action of steam 65 produced from an alkaline solution.

2. A method of permanently straightening curly hair which consists in dividing the hair in section and laying each section out straight on the rod of a hair baking apparatus, securing the hair to said rod in straightened stretched position, saturating the hair with an alkaline solution, and then subjecting it to confined heat sufficient to convert the solution into steam. 75

3. A method of permanently straightening curly hair which consists in dividing the hair in sections and laying each section out straight on the rod of a hair baking apparatus, securing the hair to said rod in straightened stretched position encasing the hair in an alkali saturated cover and then inserting it in a baking apparatus and retaining it until the solution has been converted into steam thereby changing the air currents of the hair and permanently straightening it. 85

4. A method of permanently straightening curly hair which consists in dividing the hair into sections and then holding each section 90 in straightened stretched position and subjecting it while so held to the action of steam produced from an alkaline solution.

JOHN W. EMBREY.
